UNITED STATES PATENT OFFICE.

PHILIP WUEST, JR., OF PHILADELPHIA, PENNSYLVANIA, ASSIGNOR TO THE
AUTO-MANUEL PIANO ACTION COMPANY, OF PHILADELPHIA, PENNSYLVANIA, A CORPORATION OF NEW JERSEY.

PRESSURE-REGULATOR BELLOWS.

No. 845,841.

Specification of Letters Patent.

Patented March 5, 1907.

Application filed November 7, 1904. Serial No. 231,706.

To all whom it may concern:

Be it known that I, PHILIP WUEST, Jr., of Philadelphia, in the State of Pennsylvania, have invented certain new and useful Improvements in Pressure-Regulating Bellows, whereof the following is a specification, reference being had to the accompanying drawings.

My invention may be employed with particular advantage in a mechanical musical instrument—for instance, in an instrument comprising automatic playing mechanism for sounding devices, such as piano-strings—wherein the operation is effected or controlled by atmospheric pressure opposed to a partial vacuum within a valve-chamber. In such an embodiment my improved bellows may be located between the exhaust-pumping mechanism and the valve-chamber to maintain a substantially uniform pneumatic tension within it and said valve-chamber regardless of the variations in the pneumatic tension within the exhauster, due to changes in the rate of operation of the exhaust-pumping mechanism.

My invention comprises the various novel features of construction and arrangement hereinafter more definitely specified.

The accompanying drawing is a vertical sectional view of a bellows conveniently embodying my improvements.

In said drawing, 1 and 2 are the opposed leaves of the bellows, the former being conveniently stationary with respect to the instrument casing or framework, and the latter being movable toward and away from the leaf 1 upon the hinge-joint 3 at the bottom thereof. Said leaf 1 is provided with the exhaust-port 5, leading through the nozzle 6 to the exhauster and is also provided with the port 8, leading through the nozzle 9 to the chamber in which regulated pneumatic tension is to be maintained. Said leaves 1 and 2 are connected by the collapsible diaphragm 11, which incloses the bellows-chamber 12 and folds intermediate of its width, so as to present its region 13 in opposition to said port 5, as indicated in dotted lines in the drawing, and thereby varies the effective area of said exhaust-port 5 in accordance with the position of said leaves.

The spring 14 is conveniently disposed ex-

terior to the diaphragm 11, and has its opposite ends respectively engaged with the blocks 15 and 16, which are attached to the respective leaves 1 and 2 and project beyond the edge thereof. Any tendency to increase of the degree of vacuum within said bellows-chamber 12 is compensated by a corresponding movement of the leaves 1 and 2 toward each other under pressure of the outer atmosphere and against the pressure of said spring 14, thus causing a corresponding decrease in the effective area of the port 5, so as to decrease the exhausting effect attainable through said port 5 and restore the atmosphere within the bellows-chamber 12 to the predetermined required tension. It is to be understood that the degree of pneumatic tension within said bellows-chamber 12 and the valve-chamber connected therewith may be varied in accordance with the adjustment of the effective pressure of said spring 14.

I do not desire to limit myself to the particular embodiment of my invention above specified or to the particular construction and arrangement herein set forth, as various modifications may be made therein without departing from the essential features of my invention.

I claim—

1. A pneumatic - pressure - regulating bellows, comprising opposed leaves one of which is movable relatively to the other, and provided with a port, and a collapsible diaphragm connecting said leaves, said diaphragm being free to close over said port and thereby vary the effective area of said port.

2. A pneumatic - pressure - regulating bellows, comprising opposed leaves one of which is movable relatively to the other, and provided with a port in one of said leaves; a collapsible diaphragm connecting said leaves, said diaphragm being arranged to vary the effective area of said port in accordance with the position of said leaves; and, a spring tending to separate said leaves, substantially as set forth.

3. A pneumatic - pressure - regulating bellows, comprising opposed leaves, one of which is movable relatively to the other, provided with a port leading to an exhauster and a port leading to a pneumatic valve-chamber; and, a collapsible diaphragm connecting said

leaves, said diaphragm being arranged to vary the effective area of one of said ports, substantially as set forth.

4. A pneumatic - pressure - regulating bellows, comprising opposed leaves one of which is movable relatively to the other, and provided with a port; and a collapsible diaphragm connecting said leaves and forming one wall of the bellows inclosure, said diaphragm being free to close over said port and thereby vary the effective area of said port in accordance with the position of said leaves, substantially as set forth.
5. A pneumatic - pressure - regulating bel-

lows, comprising a stationary and a movable leaf and provided with a port; and a collapsible diaphragm, said port being in such relation to the diaphragm that the motion of the latter incident to its collapse causes a portion of the diaphragm to obstruct the port and vary its effective area.

In testimony whereof I have hereunto signed my name, at Philadelphia, Pennsylvania, this 4th day of November, 1904.

PHILIP WUEST, JR.

Witnesses:

ARTHUR E. PAIGE,
ANNA F. GETZFREAD.

It is hereby certified that the name of the assignee in Letters Patent No. 845,841, granted March 5, 1907, upon the application of Philip Wuest, Jr., of Philadelphia, Pennsylvania, for an improvement in "Pressure-Regulator Bellows," was erroneously written and printed "The Auto-Manuel Piano Action Company," whereas said name should have been written and printed *The Auto-Manual Piano Action Company*; and that the said Letters Patent should be read with this correction therein that the same may conform to the record of the case in the Patent Office.

Signed and sealed this 19th day of March, A. D., 1907.

[SEAL.]

F. I. ALLEN,
Commissioner of Patents.
